ADJUSTABLE AUTOMOBILE SEAT.

Application filed November 16, 1925. Serial No. 69,462.

The invention relates to vehicle seat construction and more particularly to an attachment for tilting front seats of automobiles adapted to provide a longitudinal adjustment of the seat with respect to the vehicle.

One of the objects of the invention is to provide a device assembled as a unit which may be quickly and easily attached to a tiltable seat to render it adjustable longitudinally of the vehicle.

Another object is to provide a construction having means for relatively moving the seat with respect to the vehicle which is automatically self-locking in a plurality of positions of adjustment.

Still further objects reside in the features of construction as hereinafter described and more fully set forth and illustrated in the accompanying drawings wherein:

20 Figure 1 is a section showing a seat provided with a device embodying our invention;

Figure 2 is a bottom plan view of the attachment;

25 Figure 3 is a transverse section on line 3—3 of Figure 2.

Figure 4 is a perspective view of a modified construction, formed principally of sheet metal.

30 Figure 5 is a longitudinal section on line 5—5 of Figure 2.

Referring now more particularly to the embodiment of our invention illustrated in the drawings, A represents the front stationary posts or brackets for pivotally supporting a seat B, the latter being provided with the rear legs B' resting on the floor of the vehicle and being also preferably provided with a back B² hingedly secured at B'. This type of seat construction is commonly used for 35 the front seat of automobiles of the so-called coach type and it is usual to provide brackets rigidly attached to the underside of the seat and pivotally connected to the posts A.

According to our invention the brackets depending from the underside of the seat are 40 removed and in their place we substitute the construction illustrated in plan view in Figure 2 which comprises essentially two frame members C and D slidably connected together to form a single unit. The frame C is secured to the underside of the seat in any suitable manner preferably by means of screws extending through the apertures C' formed in the frame. At the side edges of the frame 45 C are flanges which have formed therein the grooves E' for receiving the side edges of the

frame D. The central portions of frames C and D are preferably cut-away leaving the transverse connecting portions C² and D² respectively. The frame C is also provided with two parallel racks F and F' and as shown in Figures 2 and 3 the racks being formed by a series of spaced lugs G projecting from the face of the frame C. The frame D is provided with two transverse flanges H having the aligned apertures H' therein for engaging the pivot pin I extending through the posts A. J is a shaft mounted in apertures J' in the flanges H and having one end thereof projecting outward beyond the frame C for receiving a handle or an adjustable wheel K. The shaft J has fixed thereon the two pinions L and L' each of which engages one of the racks G. A coil spring M is arranged between the pinion L and the flange H thereby urging the shaft J axially in one direction until the pinion L' engages the adjacent flange H. This flange has a detent N projecting therefrom adapted to engage between the detent of the pinion L' to prevent rotation thereof. The detent, however, may be released from engagement with the pinion by axially moving the shaft J in opposition to the spring M and the spacing between the two flanges H is sufficient to permit of the necessary axial movement. In both axial positions of adjustment, however the pinions are in engagement with the respective racks so that by rotation of the handle K, the frames C and D are given a sliding movement with respect to each other.

In order to limit the adjustment of the frames C and D, suitable stops are provided and as shown there are the raised portions O at the ends of the racks against which the teeth of the pinion strike when the extreme movement of the frames is reached. The pinion teeth thus tend to ride upon the raised lugs O and in so doing exert a lateral thrust between the two frames, but since the lateral movement of the frames is limited by the guideways E' further rotation of the pinion is prevented.

The advantages of the construction as above described will be readily apparent. The device may be quickly attached to the underside of the seat and pivotally fastened to the supporting posts A so that the seat may be tilted forward in the usual manner. The construction however, provides the further advantage of permitting longitudinal adjustment of the seat relative to the vehicle

to adapt the same to the requirements of the driver. In order to effect this adjustment the shaft J is moved axially by pressure against the hand wheel K, thus releasing the 5 detent N and the frame C can then slide relative to the frame B. The sliding movement may be effected either by rotation of the hand wheel K or by moving the seat directly. The occupant can thus adjust the seat to the desired 10 position while remaining seated. One of the features of the construction is due to the fact that the device is automatically self-locking so that as soon as the axial pressure on the hand wheel K is released, the pinion 15 will at once be forced into locking engagement with the detent.

It will be observed that when the supporting post A is of greater length than the rear legs B' a forward movement of the seat B 20 will also raise the forward end of the seat, as clearly indicated in Figure 1, by the dotted lines which represent the adjusted position of the seat.

In the construction as above described, the 25 frames C and D are preferably made of castings, but the device is readily adapted for construction of pressed sheet metal parts and Figure 4 shows a modification for this type of manufacture. In this case the main frame 30 Q has the raised portion R in which are arranged a series of perforations R' for engaging the teeth of the pinions. The edges of the frame Q are also bent into U shaped form to provide the longitudinal guide ways Q' for 35 the co-operating frame member S. This latter frame has the transversely bent flanges S' struck up from the metal plate, in order to form the bearings for the shaft J and the brackets for attachment to the posts A. In 40 this modification one of the brackets S' is also provided with a laterally bent flange S'' forming the detent for locking the pin. In order to pivotally attach the frame member S to the vehicle, lugs T are provided which 45 are preferably welded to the frame, thereby providing a construction permitting the location of the lugs to correspond with the stationary posts A on the vehicle.

The lugs T are preferably constructed of 50 U shaped form in order to embrace the posts A and are provided with aligned apertures T' for receiving the pivot pin.

In both of the constructions as above described it will be noted that two lugs are 55 provided, each arranged adjacent to one of the guide ways on the frame. There are also two pinions, each fixed upon the shaft so that both sides of the frames are adjusted simultaneously thereby preventing any binding 60 of the frames while being adjusted. Another feature of the device is the arrangement whereby the seat is tilted to a slightly different angle in each of the positions of longitudinal adjustment. By reason of this con-

struction, the operator of the vehicle is enabled to change his position in the car and it has been found that this slight adjustment is very restful especially where the driver is seated in the car for a long period of time. 65

What we claim as our invention is:

1. An attachment for vehicle seats comprising a frame adapted to be attached to the underside of the seat, a second frame adapted to pivotally engage a supporting member on the vehicle, parallel guide ways on one of said frames slidably engaging the other frame and forming a structure separable from both the seat and the vehicle as a unit, a rack carried by one frame, a rotatable and axially movable shaft in the other frame, a pinion 80 on said shaft engaging said rack, a detent on the shaft-carrying frame, spring means normally holding said pinion in engagement with said detent, and a handle on said shaft for axially moving the latter to disengage said pinion from said detent, said handle being also adapted to rotate said pinion. 85

2. In a vehicle seat, the combination of a frame having a pair of spaced parallel guide ways, a second frame longitudinally slidably in said guide ways, a rack on one frame, a shaft journaled in the other frame, a pinion fixed on said shaft and engaging said rack, a detent on the shaft-carrying frame engageable with said pinion, a spring for axially moving said shaft toward said detent, and a handle on said shaft for axially and rotatably moving the same. 95

3. In a vehicle seat, the combination with a frame having spaced parallel guide ways thereon, a second frame slidable in said guide ways, a pair of racks formed on one frame member parallel to said guide ways, a shaft journaled in the other frame member adapted to move axially, a pair of pinions fixed on said shaft each engaging one of said racks, a pair of stops limiting the axial movement of said shaft, a detent engageable with one of said pinions, a spring urging said pinions toward said detent, a handle fixed on said shaft, raised portions at the ends of said racks forming stops engageable with said pinions in the extreme opposite positions of adjustment of said frames. 100

4. An attachment for vehicle seats comprising a frame adapted to be attached to the underside of the seat, a second frame adapted to pivotally engage a supporting member on the vehicle, means including an axially movable and rotatable shaft for adjusting one frame with respect to the other, and means operable upon axial movement of the said shaft for locking one frame against movement with respect to the other. 115

5. In combination, a pair of frames, one adapted for attachment to a vehicle seat and the other adapted for attachment to the vehicle, a rack on one of the frames, a shaft 120

on the other of the frames, a pinion on stantly urging said shaft and pinion axially
the shaft meshing with the said rack, the into said locking position. ¹⁰
said shaft and pinion being mounted for In testimony whereof we affix our signa-
axial movement and being rotatable for ad- tures.

5 justing the one frame with respect to the other, means operable upon axial movement of the shaft and pinion for locking the frames against movement, and means con-
